RAILWAY SWITCH

Anthony Shacikoski, Salina, Pa.

Application April 10, 1937, Serial No. 136,183

3 Claims. (Cl. 246—412)

This invention relates to railway switches and particularly to means for throwing the switch points.

The general object of the invention is to provide a very simple and positively operating switch in which the operating lever for the points extends longitudinally of the track and in which this operating lever is itself resilient so that as the points or rails wear, the lever may be shifted to an extent which will positively carry the points against the rails and provide means for locking the lever in this shifted position.

Another object is to provide means whereby the pressure exerted by the resilient switch lever may be increased or decreased at will, so that if the space between the rails should accidentally widen or the bolts holding the rails to the sleepers or the points to the rails should become loosened, the switch operating lever may be shifted a proper distance to take up this wear or looseness.

Other objects will appear in the course of the following description.

My invention is illustrated in the accompanying drawing wherein:

Figure 1 is a top plan view of a section of track and the switch points thereof together with my improved operating means.

Figure 2 is an elevation of the means for holding the switch lever in the thrown position of the points, the lever being shown in section.

Figure 3 is a top plan view of that portion of the switch lever which engages the rack.

Figure 4 is an underside perspective view of that portion of the switch lever shown in Figure 3.

Referring to the drawing, A designates the main rails of the track, B the siding rails, and C the switch points. The switch points are connected to the siding rails in any usual or suitable manner and braced as usual. The switch points are connected by the bridle 10, as usual, and the bridle is connected by a link 11 to the lever 12. This lever is pivoted at 13 between the tie and the strap 14 which extends over the tie. The lever 12 extends longitudinally of the track and this lever is preferably formed of a sufficiently strong but relatively thin bar of steel or other suitable metal. The forward portion of the lever is horizontal. The strip of metal is twisted, however, at 15, so that the rear portion of the lever is disposed with its edge upward. The lever operates over an arcuate rack designated generally 16, which at its middle is offset at 17, this offset portion extending parallel

to the track rails A. That portion of the rack 16 which is nearest to the track is provided with notches 18 which extend downwardly and outwardly that is, away from the track, as shown best in Figure 2. The outer portion of the rack 16 away from the rails A is provided with a plurality of downwardly and inwardly extending notches 19 which extend downward and toward the track. The lever 12, as shown in Figures 3 and 4, is provided on that portion which operates over the rack with the two lugs 20 and 21. These lugs extend downward and outward in opposite directions and the lugs have the same angle as the angular notches 18 and 19, respectively. The lug 20 engages in any one of the notches 18 while the lug 21 engages in any one of the notches 19.

The switch lever is inherently resilient, particularly as regards that portion of the lever extending from the twist 15, so that the lever may be "sprung", as shown in dotted lines in Figure 1 in its plane of movement. By forming the lever of resilient material and providing the rack 16, the lever may be always pulled to a position where the points C will be brought tightly against the rails A. If, in the ordinary throw of the lever, the points should not be brought tightly against the rails, then the lever is pulled still further and lowered into an advanced notch 18 or 19, as the case may be, and this will flex the lever and cause it to resiliently press or urge the points against the rails. The spring pressure may be increased by forcing the handle to an advanced position on the rack, thereby holding the switch points firmly to the rail so that they will not move when trains pass over the points. If the lever 12 were rigid, as is usual in switches of this kind, it would be impossible to throw the points fully and tightly against the rails if the rails spread even a slight amount or if there was any play between the parts. This often leads to the cars "splitting a switch" and this ordinarily leads to derailment of the train. This is entirely prevented in my construction.

What is claimed is:

45

1. The combination with a track and a switch point coating therewith, of a lever pivoted adjacent one end, the long end of the lever constituting a handle, the long end of the lever being resilient and yieldable in the direction of movement of the lever, and means for holding the handle end of the lever in any one of a plurality of positions with the handle end of the switch lever under stress.
2. The combination with rails and switch

55

points, of a switch lever pivotally mounted at the side of the track for movement in a horizontal plane, the switch lever consisting of a metallic rod having initial resilience, the rod being twisted intermediate its ends so that the forward portion of the lever is disposed with its edges in a vertical plane, the forward portion of the lever being pivotally supported and being operatively connected to the switch points, the rear portion of the lever being disposed with its edges in a horizontal plane, and an arcuate rack over which the rear portion of the lever moves, the rack having a plurality of notches on each side of its middle with which the handle of the lever is adapted to engage.

3. The combination with a railway track having two rails and two switch points coacting

therewith, of a point shifting lever pivotally mounted adjacent one end for movement in a horizontal plane, the lever at one end being operatively connected to the points, the lever being composed of a metallic bar twisted intermediate its ends, that portion of the lever forward of the twist being disposed in a horizontal plane and that portion of the lever rearward of the twist being disposed in a vertical plane whereby the rear portion of the lever is resiliently yieldable, and an arcuate rack over which the lever operates, the rack having two sets of notches convergently inclined downward with relation to each other, the lever having two downwardly and outwardly extending lugs each coacting with one set of notches. 5 10 15
